UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A HANDLE FOR BRUSHES, &c.

SPECIFICATION forming part of Design No. 18,975, dated March 26, 1889.

Application filed February 16, 1889. Serial No. 300,170. Term of patent 7 years.

To all whom it may concern:

Be it known that I, HENRY BERRY, a citizen of the United States, residing at Shelton, in the county of Fairfield and State of Connecticut, have invented and produced a certain new and original Design for a Handle for Brushes and Like Articles, of which the following is a specification, reference being had to the accompanying drawing, which forms a part thereof, and which shows a plan view of a handle shaped and ornamented in conformity with my design.

The leading and distinctive features of my design consist in the shape or outline of the handle and in the several series of bead-like figures which appear upon the surface thereof. At its top portion, *a*, the handle is enlarged and rounded in outline, one side thereof being curved somewhat more sharply than the other, and from this enlarged portion the handle is curved downward, diminishing in size meanwhile. Near its bottom end it is curved out-

wardly, as at *b*, and then the extremity is turned upwardly and is convolved, as at *c*, to form the finished extremity of the handle. 25 Upon the surface of the handle appear representations of beaded figures *d*, which cross the handle from side to side in sinuous lines.

I claim—

The design for handles for brushes and similar articles, as herein shown and described, the same being enlarged at its top portion and curved and tapered thence downward, and having its extremity convolved and turned upwardly, and the surface of said handle having thereon the sinuous beaded figures extending across its surface, as specified. 30 35

In testimony whereof I affix my signature in presence of two witnesses.

HENRY BERRY.
